DEFLECTABLE ANTENNA

Leo J. Hruska, Merchantville, N. J., assignor to
 Radio Corporation of America, a corporation of
 Delaware

Application November 30, 1935, Serial No. 52,313

5 Claims. (Cl. 250—33)

My invention relates to a deflectable antenna. More specifically, my invention is a deflectable vertical rod antenna for mobile use. My antenna is particularly useful on motor cars where the 5 antenna may be deflected without damage to itself if it strikes an obstruction.

The sensitivity of a receiving antenna is proportional to its length and effective height. An 10 automobile antenna which does not project above the roof of the automobile has an extremely low effective height. If a fixed vertical rod antenna is used on an automobile or the like, it may meet with obstructions which would cause damage to the antenna. I am aware of numerous vertical 15 rod antennas which have been used on mobile units. Many attempts have been made to devise a deflectable antenna for such use. It is important that the antenna remain rigid during movement of the vehicle because vibration of the 20 antenna may lead to poor reception. It is likewise important that the deflectable portion of the antenna give way upon striking obstructions.

One of the objects of my invention is to provide a deflectable rod antenna.

25 Another object is to provide a deflectable antenna which will remain rigid during normal movement of the mobile unit.

Another object is to design a deflectable antenna which will have good electrical conductivity 30 at its flexible coupling.

Another object is to design a deflectable antenna which will deflect in any direction without damage to itself.

Other objects will be apparent from the accompanying specification, drawing, and appended 35 claims.

In the accompanying drawing Figure 1 is an illustration of one embodiment of my invention on an automobile,

40 Fig. 2 is a sectional view of one embodiment of the flexible coupling employed in my deflectable rod antenna, and

Fig. 3 illustrates a modified installation of my 45 antenna.

In Fig. 1 an insulating base 1 is attached to the running board 3 of an automobile 5. On the insulating base 1 is attached a fixed section of a vertical rod antenna 7 whose height is approximately equal to the top of the automobile. Securely fastened to the free end of the vertical 50 rod is a cup shape universal coupling 9 to which is attached the deflectable section of antenna rod 11. A suitable lead-in (not shown) is attached 55 to the fixed section of the vertical rod and to

a radio apparatus which is usually disposed within the automobile.

One form of construction of the cup shape universal coupling is illustrated in Fig. 2. In this figure a base member 21 of brass or other suitable material is arranged with a circular shoulder 23. The upper portion of the shoulder includes a radius 25. This radius acts as a guide which permits the cup-like member 27 to freely slide over the shoulder 23 and rest securely on the 10 base member 21. The upper part of the cup-shape member includes a socket 29 which is securely fastened to the cup by brazing, welding or the like. The socket provides clearance for a 15 spring which will be described below. Within this socket is fitted a metallic tubular member 31. The upper portion of this tubular member is preferably closed by a small cap 33. This cap serves to exclude moisture which might have a deleterious effect on the antenna. The tubular 20 member is secured to the socket by threading, brazing or other suitable means.

A pin 35 is mounted on the tubular member at a distance of several inches from the base of the cup-like member. A helical spring 37 is secured to the pin 35. The lower end of the spring is suitably fastened to a screw 39 which has been threaded into the base member 21. Lock nuts are preferably arranged to prevent the screw 30 from turning due to vibration of the motor vehicle. It should be understood that the helical spring is fastened under tension so that the circular base of the cup is firmly held against the lower base member 21. The tension of this spring 35 is sufficient to normally hold the vertical tubular member in rigid engagement with the base 21.

While the spring member holds the universal joint in rigid position during normal use of the antenna, it should be understood that the spring 40 permits the antenna to deflect whenever it meets with an obstruction. Because of the universal type of the deflectable coupling, the antenna will deflect in any direction without harm to itself. Inasmuch as the top of the automobile itself 45 should clear obstructions, it will be apparent that the antenna need only deflect until it is substantially in the plane of the top of the car.

In the embodiment shown, the cup shape member will prevent water from contacting the spring 50 and internal portions of the deflecting joint when the antenna is in the vertical position. The spring has sufficient tension to provide good electrical connection between the fixed and movable part of the antenna. In certain cases a pig tail 55

connection may be employed between the two sections of the antenna.

The tension of the spring is such that the cup member 27 firmly engages its base member 21.

5 The rounded shoulder 25 on the base member aids the cup member in aligning itself as it restores from a deflected position. Although I prefer the arrangement shown, it should be understood that the cup member may be secured to the fixed 10 antenna rod and the base member 21 may be secured to the deflecting member. The base member may be mounted on the roof of the automobile instead of on the fixed antenna section, as shown in Fig. 3.

15 Numerous modifications within the scope of my invention will occur to those skilled in the art. It should be understood that I do not limit my invention to the precise embodiment which has been illustrated by way of example. I only intend to 20 limit my invention as required by the prior art and appended claims.

I claim as my invention:—

1. A deflectable antenna comprising a fixed section, a deflectable section, a base member mounted 25 on one of said sections, a cup shape member mounted on the other of said sections, and a spring under tension for firmly engaging said base and cup shape members, the relative shape and junction of said members being such as to insure a good high frequency contact and to exclude moisture.

2. An antenna of the character described including a base member having a circular shoulder therein, a tubular member having secured thereto 35 a cup shape member, and means for engaging under tension the base of said cup shape member and said shoulder which are so constructed and arranged that said cup and base are normally held

together and having contact portions of such relative shape that moisture is shed and a good high frequency contact is insured.

3. An antenna of the character described including a base member having a circular shoulder 5 therein, a cup shape member frictionally engaging said shoulder, the relative shape and junction of said shoulder and cup being such that moisture is shed and a good high frequency contact is maintained, a tubular member secured to said cup 10 shape member, a spring secured to said tubular member and located therein, and means securing said spring to said base member under tension so that said tubular member is normally maintained in a fixed position with respect to said 15 base, and is yieldably arranged when said tubular member is deflected.

4. In a device of the character of claim 3, means for guiding said cup shape member with respect to said shoulder as said tubular member is restored 20 to its normal position after deflection.

5. A deflectable antenna for vehicles comprising a tubular member terminating in a closed portion at one end and in a cup shape member at its other end, said cup shape member having a 25 circular base concentrically arranged with respect to said tubular member, a base member having a circular shoulder adapted to engage said circular base, said shoulder and base having a relative shape and junction which excludes moisture 30 and maintains a good high frequency electrical contact, a helical spring located within said tubular member and having one end secured thereto, and means for securing under tension the other end of said spring to said base member, 35 whereby said tubular member may be universally deflected with respect to said base member.

LEO J. HRUSKA.
